UNITED STATES PATENT OFFICE.

MOSES ROSENGARTEN, OF PHILADELPHIA, PENNSYLVANIA, ASSIGNOR, BY MESNE ASSIGNMENTS, TO FANNIE JACOBS, OF PROVIDENCE, RHODE ISLAND.

HAT-PIN.

No. 909,121.

Specification of Letters Patent.

Patented Jan. 5, 1909.

Application filed February 15, 1908. Serial No. 416,019.

To all whom it may concern:

Be it known that I, MOSES ROSENGARTEN, a subject of the Czar of Russia, and residing at Philadelphia, in the county of Philadelphia and State of Pennsylvania, have invented certain new and useful Improvements in Hat-Pins, of which the following is a specification.

This invention relates to hat pins, the object being to provide a hat pin with oppositely disposed sliding pins, which can be forced outwardly through the hat after being inserted in the hair, so as to securely fasten the hat in place.

Another object of my invention is to provide very novel means for operating the pins, whereby by simply pulling on a knob, the pins will be forced outwardly, and by pushing on the same, they will be forced inwardly.

Another object of my invention is to provide a hat pin which is exceedingly simple and cheap in construction, and one which is composed of a very few parts, which are so arranged that they are not likely to get out of order.

Another object of my invention is to provide a hat pin which will not get caught in the hair when inserted, and one which is very neat in appearance.

These objects are obtained by the novel arrangement and construction of parts hereinafter fully described and shown in the accompanying drawings, in which:

Figure 1, is a perspective view of my improved hat pin showing the application of the same. Fig. 2, is a longitudinal section view through the same. Fig. 3, is a perspective view of the tube carrying the pins detached, and, Fig. 4, is a perspective view of the hat pin.

In the drawings A, indicates a casing or sheath, oval in cross section, having a contracted end A'. In this sheath is arranged a tube B, which is slotted as shown at B', having a central stop lug C, secured therein. In this tube are oppositely disposed slidably mounted pins E and F, which are adapted to be forced out through the tube, and which are provided respectively with eyes E' and F'. The eye F' carries an S shaped member F'', to which the one end of a cord G, is connected. This cord passes through guide eyes H and I, secured on the tube in alignment with the slot, the oval end of the cord

being connected to the eye E', as shown at G'.

The casing A, is provided with a slot A², in one side, through which extends a wire J, provided with a hook J', at its inner end, 60 adapted to engage the eye F', and provided at its outer end with a knob J². The tube B is secured within the casing by solder, and the end of the casing is closed by a cap K, provided with an opening in alinement with 65 the end of the tube, through which the pin F, is adapted to extend when the wire is drawn outwardly. It will be seen by connecting the pins together by a cord passing through the eyes arranged on each end of the tube, that the pins will be drawn outwardly as the eye F' is drawn towards the end of the slot and forced inwardly as the eye is forced towards the central stop lug C.

The operation of the pin is as follows: 75 When it is desired to secure a hat in place, the pin is forced through the hair so as to allow the knob to drop down to one side of the head, and the hat is placed on the head. By drawing downwardly on the knob, the pins 80 will be forced out through the hat, so as to securely hold it in place.

Having thus described my invention what I claim as new and desire to secure by Letters Patent is:

1. A hat pin comprising a sheath open at both ends, oppositely projecting pins within said sheath, a cord engaging said pins to project them out of opposite ends of the sheath and a movable wire extending into the sheath 90 and engaging the said cord whereby the pins may be operated.

2. A hat pin comprising a sheath open at both ends, oppositely projecting pins within said sheath, a cord engaging said pins to project them out of the sheath and a headed wire extending into the sheath from the exterior, said wire engaging at its end with the cord whereby the pins may be actuated.

3. A hat pin comprising a slotted tube, 100 pins mounted in said tube provided with eyes extending out through the slot of the tube, eyes formed on said tube, and a cord passing through said tube eyes and connected to the eyes of the pins.

4. A hat pin comprising a slotted tube, pins slidably mounted in said tube provided with eyes extending out through said slot, eyes formed on said tube, a cord passing through said tube eyes connected to the eyes 110

of the pins, and operating means connected to one of said pins.

5. A hat pin comprising a slotted tube, pins mounted in said tube, provided with eyes extending out through said slot, eyes formed on said tube adjacent to each end, a cord passing through the eyes of the tube and connected to the pins, and a wire connected to one of said eyes on the pins for operating 10 said pins.

6. A hat pin comprising a sheath oval in cross section provided with a contracted end, and having a slot in its side, a slotted tube arranged within said casing, pins slidably 15 mounted in said tube provided with eyes extending out through said slot, eyes formed on the ends of the sheath, a cord passing through the eyes of the tube connected to the eyes of the pins, and a wire extending through the 20 slot of the sheath connected to the eye of one of the pins.

7. A hat pin comprising a sheath having a contracted end, a slotted tube arranged

within said sheath, having a stop lug centrally arranged therein, guide eyes secured 25 to said tube, adjacent its ends, pins slidably mounted in said tube provided with eyes extending out through said slot, an S shaped hook carried by one of said pins, a cord passing through the eyes of the tube connected to 30 said S shaped hook, and to the eye of the other pin, said sheath being provided with a slot, a wire having a knob at its outer end extending through said slot, and provided with a hook adapted to be secured to one of 35 the eyes of one of the pins, and a cap arranged over the open end of said sheath, provided with an opening registering with said tube.

In testimony whereof I have signed my 40 name to this specification in the presence of two subscribing witnesses.

MOSES ROSENGARTEN.
